UNITED STATES PATENT OFFICE.

JOSEPH E. STEINMEIER, OF NEW YORK, N. Y., ASSIGNOR TO WESTERN CLOCK COMPANY, OF LA SALLE, ILLINOIS, A CORPORATION OF ILLINOIS.

DESIGN FOR A CLOCK-FRAME.

47,203.

Specification for Design.

Patented Apr. 6, 1915.

Application filed January 21, 1915. Serial No. 3,643. Term of patent 7 years.

To all whom it may concern:

Be it known that I, JOSEPH E. STEINMEIER, a citizen of the United States, and a resident of the city of New York, borough of Manhattan, in the county and State of New York, have invented a new, original, and ornamental Design for a Clock-Frame, of which the following is a specification, reference being had to the accompanying drawing, forming part thereof.

The figure is a front face view of a clock frame showing my new design.

I claim:

The ornamental design for a clock frame, as shown.

JOSEPH E. STEINMEIER.
